United States Patent Office.

GEORGE GILL, OF TAUNTON, MASSACHUSETTS, ASSIGNOR TO REED & BARTON, OF SAME PLACE.

Design No. 4,813, dated April 18, 1871.

DESIGN FOR A TEA-POT.

The Schedule referred to in these Letters Patent and making part of the same.

To all persons to whom these presents may come:

Be it known that I, GEORGE GILL, of Taunton, of the county of Bristol and State of Massachusetts, have invented or produced a new ornamental Design for a Tea-pot or Service; and do hereby declare the same to be described as follows, and to be represented in the accompanying drawing, which shows a tea-pot formed or provided with the design.

Of such drawing—

Figure 1 denotes a front elevation, and

Figure 2 a side view of such tea-pot.

The foot or base of the vase of the tea-pot has lions' heads in *alto rilievo* on its flanks, they being projected from raised panels, surmounted by leaves in relief.

The body of the vase is capped by a bell-shaped

cover surmounted by a flat knob, supported by lions' heads, and terminating at top in a cone.

The form and ornamentation of the handle and the nose or spout of the vase are duly represented in the drawing, both sides of each being alike.

The encircling chased band, with its sprigs and leaves, as shown at the upper part of the vase-body, constitutes no part of the design.

In the said tea-pot, as represented,

I claim—

The design for the vase or body, that of the cover, that of the spout or nose, and that of the handle, all being essentially as shown in the drawing.

Witnesses:

GEORGE GILL.
WILLIAM PARKIN,

WILLIAM W. SWAN.
